H. G. Shadurman,
ATTORNEY.

UNITED STATES PATENT OFFICE.

EDWARD FREEMAN GOODRUM, OF MACON, GEORGIA.

HIGHWAY SURFACE SIGNAL DEVICE.

1,357,860.

Specification of Letters Patent.

Patented Nov. 2, 1920.

Application filed August 17, 1920. Serial No. 404,156.

To all whom it may concern:

Be it known that I, EDWARD F. GOODRUM, a citizen of the United States, residing at Macon, in the county of Bibb and State of Georgia, have invented certain new and useful Improvements in Highway Surface Signal Devices; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to signals and especially refers to a signal for use in indicating the approach of a vehicle traveling over a highway to a danger point.

The object of the invention is to indicate to the operator or driver of a vehicle using a highway, such as an ordinary country road and thoroughfare, the proximity of a danger zone in the road and thoroughfare ahead such as a railroad-crossing or other like place which should properly be approached with caution, the indication being afforded by improved means requiring no exercise of the faculties of seeing or hearing but being arranged to set up a series of rapid vibrations in the vehicle.

With the above and other objects in view, as will be hereinafter apparent, the invention consists in general of certain novel arrangements of details and combinations of parts hereinafter fully described, illustrated in the accompanying drawing and specifically claimed.

In the accompanying drawing forming a part hereof, like characters indicate like parts in the several views, and

Figure 1 is a perspective view of the crossing of a railroad and highway and showing the invention installed,

Fig. 2 is a transverse section through that portion of the highway formed in accordance with the invention,

Fig. 3 is an enlarged longitudinal section through part of the highway and signaling means,

Fig. 4 is a bottom perspective view showing several of the signaling elements and the means used to hold them in position,

Fig. 5 is a diagrammatic plan view of a highway and railroad crossing with the signaling means in the highway.

In the embodiment of the invention as illustrated in the drawings there is disclosed a highway 10 which is crossed by a railroad 11 on the same level as the highway, being 60 what is commonly known as a grade crossing. Under these circumstances the railroad constitutes a danger zone for traffic along the highway and has been selected for illustration as typical of one of many conditions 65 which may occur wherein a danger zone exists on a highway.

At each side of the danger zone, and in spaced relation thereto is shown the signaling device which is indicated in general at 70 12. In the construction of these devices a suitable excavation is made in the surface of the highway and in this excavation is laid a concrete bed or foundation 13 having channel bar stringers 14 embedded therein 75 with thin flanges down and the backs of their webs flush with the top of the concrete. These stringers are bored or punched at proper intervals before being set in the concrete and through the holes thus formed are 80 passed bolts 15 the heads of which thus become embedded in the concrete as shown in Figs. 2 and 3. Each signal element consists of a tubular member 16 segmental in cross section and these members are arranged to 85 extend longitudinally across the highway with their flat or chordal sides downward and resting on the stringers and their edges touching as shown. Preferably these members are provided with longitudinal slots 90 17 in the flat sides to receive the upper ends of the bolts 15 and are held in position by the nuts 18 screwed on these bolts, access to the nuts being had through the open ends of the members 16.

With this construction forming part of the approach to a danger zone it becomes impossible for the driver or operator of a vehicle to enter such zone without being aware of its proximity because any vehicle 100 passing over the corrugated surface formed by the signal members will receive a series of vertical impulses which will effect a rapid shaking or vibration of the vehicle and all therein.

There has thus been provided an effective device for accomplishing the purposes of my invention.

Having thus described the invention, what is claimed as new, is

1. The combination with a vehicle highway having a danger zone; of means in the

highway arranged to effect rapid shaking of a vehicle passing over the highway, said means being spaced from the danger zone whereby to warn an occupant of the vehicle 5 of the approach of the latter to such danger zone.

2. The combination of a vehicle highway having a danger zone; of means in the highway spaced from the danger zone and arranged to effect a series of closely spaced substantially vertical impulses to a vehicle 10 passing over said highway whereby to notify an occupant of such vehicle of the proximity of the danger zone.

15 3. A vehicle highway having a danger zone and provided at the approach to said zone, in advance of the danger zone, with a closely corrugated surface whereby to set up rapid vibrations of small amplitude in a 20 vehicle passing thereover and thereby warn an occupant of such vehicle of his approach to said zone.

4. A vehicle highway having a danger zone, and a series of signal members set closely side by side in spaced relation to the 25 danger zone in the surface of said highway and arranged to form a series of closely spaced corrugations.

5. A vehicle highway having a danger zone and provided in spaced relation to said 30 danger zone with a recess in its surface, stringers extending longitudinally of the highway in said recess, hollow tubular members of segmental cross section extending across said highway with their sides 35 contacting and their flat sides bearing on the stringers, and means to secure the tubular members to the stringers.

In testimony whereof I affix my signature in presence of two witnesses.

EDWARD FREEMAN GOODRUM.
